Primary Examiner — Katherine Glennon

Int. Reg. No.: **DM/202373**

(74) Attorney, Agent, or Firm — Hauptman Ham, LLP

Int. Reg. Date: **Apr. 12, 2019**

(57) **CLAIM**

Int. Reg. Pub. Date: **Aug. 23, 2019**

The ornamental design for a memory card, as shown and described.

(30) **Foreign Application Priority Data**

DESCRIPTION

Oct. 12, 2018 (CN) 201830568799.3

The patent or application file contains at least one drawing executed in color. Copies of this patent or patent application publication with color drawing(s) will be provided by the Office upon request and payment of the necessary fee.

(51) LOC (13) Cl. **14-02**

1.1 is a front view of a memory card showing my new design;

(52) U.S. Cl.

1.2 is a rear view thereof;

USPC **D14/436**

1.3 is a left side view thereof;

(58) **Field of Classification Search**

1.4 is a right side view thereof;

USPC D14/432, 435-438, 479-480, 485-495;
D13/182

1.5 is a top view thereof;

See application file for complete search history.

1.6 is a bottom view thereof; and

(56) **References Cited**

1.7 is a rear perspective view thereof.
